UNITED STATES PATENT OFFICE.

THOMAS M. PUSEY, OF KENNETT SQUARE, PENNSYLVANIA.

VOLTAGE-REGULATOR.

No. 834,750.

Specification of Letters Patent.

Patented Oct. 30, 1906.

Application filed July 19, 1904 Serial No. 217,270.

To all whom it may concern:

Be it known that I, THOMAS M. PUSEY, a citizen of the United States, and a resident of Kennett Square, in the county of Chester and State of Pennsylvania, have invented a new and Improved Voltage-Regulator, of which the following is a full, clear, and exact description.

My invention relates to voltage-regulators, 10 my object being to produce certain improvements for making the regulation more perfect and also to secure certain other advantages, all of which are described below and pointed out in the accompanying claims.

Reference is to be had to the accompanying drawings, forming a part of this specification, in which similar characters of reference indicate corresponding parts in all the figures.

20 Figure 1 is a diagrammatic elevation of the general arrangement of the regulator including the wiring. Fig. 2 is a vertical central section through the solenoid 4 and parts immediately adjacent thereto. Fig. 3 is an enlarged vertical fragmentary section upon the line 3 3 of Fig. 2 looking in the direction of the arrow and showing a part of the contact mechanism for opening and closing one of the circuits. Fig. 4 is an elevation of the 25 rheostat 50 and parts immediately connected therewith, and Fig. 5 is a section through the same upon the line 5 5 of Fig. 4 looking toward the top of the sheet.

The main solenoid is shown at 4. The 30 spool 4^e of the solenoid is provided at its upper end with a plate 4^d, made comparatively thick for the purpose of supporting certain mechanical parts resting thereupon and hereinafter described, and at its other end with a 35 plate 4^e. A number of rods 5, threaded as shown, extend from the plate 4^d downwardly through the plate 4^e and are fitted with threaded nuts 6 7, which are adapted to turn thereupon. Resting upon the nuts 6 is 40 a helical solenoid 8, and upon the nuts 7 is another helical solenoid 9, these two solenoids being somewhat similar. By running the nuts 6 7 upward or downward the respective solenoids 8 9 may be adjusted relatively to 45 the main solenoid 4. The core of the main solenoid is shown at 10 and is suspended from a hook 11, engaging a link 12, this link in turn resting upon fulcrum-bearings 13, carried by a rocking beam 14, this rocking beam being further provided with fulcrum- 50 bearings 15, resting upon supporting-brack-

ets 16. Connected rigidly with the plate 4^e is a flange 17, provided with slots 18, through which pass screws 19, which engage the base 4^f. These screws may be loosened or tightened at will, so that the flange 17 may be adjusted for the purpose of maintaining the spool 4^e in proper alignment with the core 10, which hangs vertically.

The rocking beam 14 is provided with a 60 threaded portion 20, upon which is revolvably mounted a weight 21. The ends of the rocking beam are provided with terminals 22 23, which dip into vessels 24 25, containing acidulated water 26 27 or other conducting liquid, 65 the engagement between the terminals 22 23 and the liquid 26 27 occurring when the rocking beam 14 is tipped in the one direction or the other beyond certain limits, as will be seen from Fig. 1. Electrodes 28 29 are connected by wires 30 31 (see Fig. 1) with the respective helical solenoids 8 9. From the solenoid 9 a wire 32 leads to a winding 33 of a reversible motor 34, a reversal winding 35 of this motor being connected by a wire 36 80 with the helical solenoid 8. A shaft 37, revolvably mounted upon the motor 34, is provided with a worm-wheel 38, which engages a worm 39, being thereby adapted to actuate a pulley 40, from which a belt 41 passes to 85 the revolvble armature 42.

From the oppositely-coiled windings 33 35 wires 43 44 join a common wire 45, which is connected with a brush 46 of the armature 42. The other brush 47 is connected by a 90 wire 48 with a wire 49. This last-mentioned wire is connected with a rheostat 50 by means of a binding-post 51 and is also connected with an exciting-dynamo 52. The rheostat 50 is provided with another binding-post 53 and with a movable arm 54, which has a handle 55 for the purpose of rotating the same by hand should occasion so require. Limiting-stops 54^a prevent excessive movement of the arm 54, as will be understood from Fig. 4. Supported by the arm 54 is a contact member 54^b, adapted to engage contact-buttons 54^c of the rheostat 50. Screws 56 pass through the arm 54 and carry a friction-plate 57, which engages a friction-disk 58, the latter being rigidly connected with a worm-gear 59, which is in turn actuated by a worm 37^a on the shaft 37. Generally speaking, the action of the arm 54 is the same as that of any other rheostat-arm, its movement in one direction increasing the resistance of the rheostat and in the opposite

direction decreasing the same. Because of the frictional engagement between the members 57 and 58, however, the movement of the arm 54 is not necessarily positive, and in 5 extreme cases the arm 54 may slip relatively to the gear 59. This arrangement is for the purpose of preventing breakage of the arm 54 or other part of the rheostat in case the movement of the worm 37^a is not stopped 10 promptly and is carried too far, owing to the momentum of the revoluble armature 42. If the armature 42 acquires such momentum that when the current passing through it is cut off, the armature keeps on running, the 15 arm 54 encounters one or the other of the limiting-stops 54^a, and hence the disk 53 merely slips upon the plate 57, so that the arm 54 stops upon reaching its proper limit in either direction. The friction-disk 53 and 20 the worm-gear 59 are loose relatively to the shaft 60, but normally held in a position of comparative rigidity by the friction between the friction-disk 53 and the friction-plate 57. By means of the screws 56 these last-mentioned 25 members are readily tensioned relatively to each other, so as to increase or diminish the amount of friction therebetween. These members therefore constitute a type of adjustable clutch.

30 Mounted upon the plate or spool end 4^d, which is in turn mounted upon the base 4^c, is a bracket 4^e, provided with an adjustable screw 61, having a contact-point 62, which engages a contact-spring 63, this spring being 35 mounted upon the plate 4^d and adapted to engage a limiting-stop 64^a, as indicated more particularly in Fig. 2. From this spring 63 a wire 64 leads to the beam 14. A choking-coil 65 is connected with wires 66 67 and is 40 provided with a manually-operated core 68 for the purpose of increasing or decreasing its inductance. A hand-switch 69 is provided for the wire 67 and is used for opening and closing the same. The wire 66 is connected 45 with a wire 70, which extends from the solenoid 4 to the secondary winding 73 of a transformer 71. Connected with this same secondary winding is a wire 72, which leads back to the solenoid 4. While the wires 70 50 and 72 represent the terminals of the solenoid 4, the wire 67 taps the solenoid 4^a at a junction 4^b intermediate of the terminals, so that a portion of the solenoid 4 (see top of Fig. 1) is in parallel with the wire 67 and with 55 the choking-coil 65 with reference to the circuit through the secondary winding 73 of the transformer, and yet another portion of the winding 4 is in series with the wire 67 and the choking-coil 65 and is also in series with the 60 wires 70 and 72. When an alternating current flows from the secondary winding 73 through the wires 70 and 72, a part of the current from the wire 70 divides off and passes in parallel through the choking-coil 65. 65 While, therefore, the main current from the

secondary winding 73 passes serially through the wire 72, all of main solenoid 4, and thence through wire 70, a part of the current is diverted and passes through the wire 66, choking-coil 65, switch 69, wire 67, thence through 70 a part only of the main solenoid 4, the path of the current otherwise being the same as that through the wires 70 and 72.

By adjusting the core 68 of the choking-coil 75 the inductive resistance of the latter may be varied at will, so that the magnetic effect upon the solenoid 4 with reference to the core 10 may be varied within certain limits at will. A lamp 75 is connected with the secondary winding 73 and with the wire 70. By means 80 of the lamp 75 and the choking-coil 65 the constants of the ohmic resistance and inductance of the secondary circuit may be regulated at will within certain limits. An alternating generator is shown at 79 and is connected with line-wires 80 and 80^a. From the generator 79 shunt-wires 80^b 81 connect with the primary winding 74. The field-winding of the generator 79 is shown at 82 and is connected by wires 83 84 with the binding-post 90 95 53 of the rheostat 50 and the exciting-dynamo 52, respectively. The exciting-dynamo is in turn connected by a wire 49 with the binding-post 51 of the rheostat.

The circuit of the main current supplied by 95 the generator 79 is as follows: generator 79, wire 80 to line, thence returning through wire 80^a to generator. A shunt-circuit through primary winding 74 is as follows: generator 79, wire 80^b, primary winding 74, and wire 100 81 back to generator 79.

The action of my device is as follows: The 105 alternating generator 79 being in action, currents pass through the line-wires 80 80^a and also through the shunt-circuit connected with primary winding 74, as just described. The currents through the primary winding 74 thus energize the transformer and induce other alternating currents through the secondary winding 73 and wires 70 and 72. The core 68 of the choking-coil 65 is now adjusted according to the voltage desired—that is to say, at one time it may be desirable to have the voltage higher than at another time—as, for instance, when the current is used during 110 the earlier part of the night to a greater extent than during the latter part thereof. The 115 secondary or induced currents now flow through the main solenoid 4, energizing both parts thereof, the upper part of the solenoid being unaffected by the inductive resistance 65 and the other part of the solenoid 4 being affected to the extent that the current passes proportionately between it and the inductive resistance 65. The main solenoid 4 is thus 120 energized and lifts the core 10 a slight distance, thereby balancing the beam 14 and rendering the same substantially level. The 125 circuit of the secondary or induced currents is as follows: secondary winding 73, wire 72, 130

solenoid 4, wire 70, lamp 75 back to secondary winding 73. From this circuit a parallel circuit branches off at the junction 4^b and passes through wire 67, switch 69, inductance-coil 65, and wire 66 to wire 70, where it rejoins the circuit.

The normal position of the beam 14 while the apparatus is idle is such that the right-hand portion 14^a of the beam is downward and rests upon the spring-contact 63, breaking contact between it and the contact-point 62 of the screw 61. When, therefore, the core 10 is raised, as above described, the beam 14 no longer engages the spring-contact 63, which thereupon raises and closes against the contact member 62. This action does not leave the circuit closed, for the reason that at this time neither of the members 22 23 touches its liquid 26 or 27. If now the voltage rises too high, the left-hand portion of the beam 14 tips, so that the member 23 engages the liquid 27, thereby completing the following circuit, which is in parallel with the circuit through the field-winding 82: exciting-generator 52, wires 84 85, metallic bracket 4^c, screw 61, spring 63, (see Fig. 3,) wire 64, beam 14, liquid 27, wire 31, helical solenoid 9, wire 32, winding 33 of the motor 34, wire 43, wire 45, brush 46, armature 42, brush 47, wire 48, and wire 49 back to the exciting-dynamo 52. This starts up the motor 34, causing the armature thereof to revolve, and the armature sets in motion the train of gearing 41, 40, 38, 37, and 59, thereby causing the arm 54 of the rheostat 50 to move in a predetermined direction, so as to increase the resistance through the rheostat 50. As the rheostat controls the current passing through the field 82 of the main generator 79 and as the resistance of the rheostat is thus varied, the current through the field 82 is cut down accordingly, with the result that the voltage passing through the main wires 30 80^a 81 and through the transformer 71 is reduced to a point approximating the normal. The circuit through the liquid 27, above described, also energizes the helical solenoid 9, causing it to pull the core 10 downward. Were it not for the action of the helical solenoid 9 the core might be drawn too suddenly upward, might "race," so to speak. The pull of the solenoid 9 upon the core 10 gently restores the beam 14 to a position approximating that which it normally occupies when the device is in action, the electrode 23 being raised out of the liquid 27. If now from any cause the voltage from the secondary winding decreases, the core 10 drops downward, so that the electrode 22 is brought into engagement with the liquid 26. The following shunt-circuit is thus completed: exciting-dynamo 52, wire 84, wire 85, metallic bracket 4^c, contact members 62 63, wire 64, beam 14, electrode 22, liquid 26, wire 30, helical solenoid 8, wire

36, winding 35, wire 44, wire 45, armature 42, wires 48 and 49 back to exciting-dynamo 52. This energizes the motor 34, and as the winding 33 is in a reverse direction to the winding 35 the direction of rotation of the armature 42 is reversed, thereby causing the arm 54 of the rheostat 50 to move in a direction contrary to that above described. The circuit just traced also energizes the helical solenoid 8, which thereupon exerts a gentle lifting action upon the core 10, so as to raise the same and also to prevent any racing action thereof due to the abrupt pull of the solenoid 4 thereupon. The beam 14 again becomes approximately level and contact between the electrode 22 and the electrode 26 is broken. It follows, therefore, that within reasonable limits, where the voltage is not subject to abrupt excessive variations, it is maintained approximately equal, the apparatus being self-governing. Of course the opposite movements of the armature 42 cause opposite movements of the rheostat-arm 54, and consequently cut the resistance out or in, according to the direction of the armature 42, this direction being governed according to whether the circuit is completed through the liquid 27 or through the liquid 26, or, in other words, according to whether the beam 14 tips in one direction or the other. It will be understood that the tendency of the solenoid 4 alone to raise the core 10 when the voltage becomes excessive and to allow the core to descend when the voltage drops too low is to complete the circuit through the wires 31 and 30, respectively, according to the intensity of the current flowing through the main solenoid 4. It therefore necessarily follows that the tendency of the solenoid 4 is to keep the beam 14 in such position as to maintain the voltage approximately uniform through the medium of the rheostat 50. If now from any cause there is a sudden and unusual drop in the voltage of the main circuit, the core 10 plunges downward and the beam 14 rocks, so that the electrode 22 penetrates deeply the liquid 26, the motion of the beam 14 causing the spring 63 to descend and break contact with the screw 61, so as to leave the circuit open through the windings 33 and 35. The spring 63 thus serves as a safety device. It is so adjusted as to allow the motor-current to be broken in case there is a short circuit on the generator or upon any part of the main line or in case of a dangerous overload tending to lower the potential to a critical degree or even in the event of a break in the circuit of the solenoid 4. The rheostat 50 is now powerless to move, so that sudden and abrupt drops in the potential are unable to disturb it. As the armature 42 necessarily has more or less momentum, the helical coils 8 9 may be adjusted so as to partially compensate for its momentum. Any sudden rise in potential is at once corrected

by the resulting action of the rheostat 50. The helical coils 8 and 9 do not exert any checking action in overcoming the momentum of the armature 42. The helical coils 8 and 9 cause the current through the armature 42 to be taken a little earlier, that is to say, they cause the current through the armature 42 to be broken before the rheostat 50 has reached its proper position and generated the voltage. The momentum of the armature 42 will then move the rheostat-arm 54 to its proper position by the time the armature 42 comes to rest.

A further safeguard against damage by virtue of the momentum of the armature 42 is found in the fact that the plate 53 (Fig. 3) can slide upon the friction-plate 57 when the torque between the rheostat-arm 54 and the gear 59 exceeds a certain limit. If, therefore, the arm 54 reaches one or the other of its limits and the armature 42 continues to move in spite of the checking action of the helical solenoid 8 or 9, no harm can occur to the rheostat, for the reason that when the arm 54 reaches its limit and stops the further rotation of the gear 59 merely causes the friction-disk 58 to slip upon the friction-plate 57. The sensitiveness of the adjustment between these two friction members being controllable by means of the screws 56, it follows that the slip can be effected with any degree of pressure desired.

Having thus described my invention, I claim as new and desire to secure by Letters Patent—

1. In a voltage-regulator, the combination of a main solenoid provided with a movable core, contact mechanism to be opened and closed by movements of said core, and helical solenoids encircling said core for the purpose of preventing the same from racing, said helical solenoids being connected with said contact mechanism.

2. In a voltage-regulator, the combination of a main solenoid provided with a movable core, contact mechanism to be opened and closed by movements of said core, helical solenoids encircling said core and adapted to prevent the same from racing, and means controllable at will for adjusting the relative positions of said helical solenoids.

3. In a voltage-regulator, the combination of a solenoid having inner and outer windings, a core energized by said solenoid and movable relatively thereto, electric mechanism controllable by movements of said core for governing the current passing through said

solenoid, a wire connected with said inner winding, another wire connected with said outer winding, said windings being in series, means for energizing said wire, a shunt-circuit connected with one of said wires and connected with said solenoid at the junction-point between said inner winding and said outer winding, being thus connected in parallel with one of said windings or in series with the other of said windings, and means controllable at will for governing the inductive resistance of the circuit thus mentioned.

4. In a voltage-regulator, the combination of a solenoid provided with a movable core, a rocking beam connected with said core and movable therewith, said rocking beam being provided with electrodes, vessels disposed adjacent to said electrodes and provided with conducting liquids into which said electrodes may dip separately, an electric circuit for controlling said solenoid, and bellied solenoids connected electrically with said vessels, and controllable by currents passing through the same for the purpose of preventing undue movement of said core.

5. In a voltage-regulator, the combination of a solenoid provided with a movable core, a rocking beam connected with said core and movable therewith, said rocking beam being provided with electrodes, vessels disposed adjacent to said electrodes and provided with conducting liquids into which said electrodes may dip separately, an electric circuit for controlling said solenoid, helical solenoids connected with said vessels and controlled by currents passing through the same for preventing undue movement of said core, and means for adjusting said helical solenoids relatively to said last-mentioned solenoid.

6. In a voltage-regulator, the combination of a solenoid provided with a plurality of windings, and also provided with a movable core, separate wires connected with said windings individually, another wire connected with both of said windings in common, an inductive resistance connected with said last-mentioned wire, and contact mechanism connected with said core and actuated by movements thereof for controlling the current through all of said wires.

In testimony whereof I have signed my name to this specification in the presence of two subscribing witnesses.

THOMAS M. PUSEY.
